CLAIM

The ornamental design for a personal watercraft, as shown and described.

DESCRIPTION

FIG. 1 is a perspective illustration, from the front and right side, of the personal watercraft of our design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Where included, broken lines showing environment or structure are for illustrative purposes only and form no part of the claimed design.

The omission of a view indicates that the omitted view is plain and unornamented.
